United States Patent

Des. 240,348
Patented June 29, 1976

240,348

CHAIR

Svante Schoblom, Pipplarp, S-573 00, Tranås, Sweden

Filed July 16, 1974, Ser. No. 488,978

Claims priority, application Sweden Jan. 18, 1974

Term of patent 14 years

Int. Cl. D6—01

U.S. Cl. D6—31

FIG. 1.

FIG. 2.

FIG. 3.

FIG. 1 is a front perspective view of a chair, showing my new design;

FIG. 2 is a rear perspective view of the chair of FIG. 1, showing my new design;

FIG. 3 is a side perspective view of the chair of FIGS. 1 and 2, showing my new design.

The side of the chair not shown in the figures is the mirror image of the side shown in FIG. 3.

I claim:

The ornamental design for a chair, as shown and described.
